UNITED STATES PATENT OFFICE

WYLIE G. WILSON, OF ELIZABETH, NEW JERSEY, ASSIGNOR TO EVERLASTING VALVE COMPANY, OF JERSEY CITY, NEW JERSEY, A CORPORATION OF NEW JERSEY

VALVE

Application filed February 25, 1928. Serial No. 256,887.

This invention relates particularly to valves of the type in which the sealing element is a disc cooperating with a sealing face surrounding the valve port and arranged in the valve opening movement to slide in contact with a lateral continuation or extension of the sealing face.

Special objects of the invention are to prevent the accumulation of sediment or solid matter from interfering with the proper opening, closing and sealing of the valve and to provide a simple, practical form of valve structure, adaptable for continuous, effective use in the handling of fluids carrying more or less solid matter.

The foregoing and other desirable objects are attained by a novel form of valve structure, including in particular, a novel arrangement of valve parts wherein the sealing element is enabled to travel in a free or non-constricted space so that in its movement it may clear away any solid matter lying in its path without binding such solid matter against an abutment such as might restrict the opening or closing action of the valve.

Various other novel and important features of the invention will appear in the course of the following specification.

The drawings accompanying and forming part of the specification, illustrate different embodiments of the invention and it should be understood that the structure is capable of further modification and change without departure from the true scope and spirit of the invention as hereinafter described and broadly claimed.

Figure 1 is a broken vertical sectional view showing an embodiment of the invention as a tank valve in a locomotive tender, said view being taken as on substantially the plane of line 1—1 of Figure 2.

Figure 2 is a broken plan view of the valve shown in Figure 1.

Figure 3 is a broken side elevation, showing the use of one form of the valve with the dust removal pockets of a gas flue.

Figure 4 is a broken vertical sectional view of the latter form of valve as on substantially the plane of line 4—4 of Figure 5.

Figure 5 is a horizontal sectional view of

the valve as on substantially the plane of line 5—5 of Figure 4.

The base 7 of the valve is constructed according to the particular needs or uses to which the valve is put. In the case of the construction first shown, this base is made with a flange 8 by which the same may be bolted to the tank 9 and in the construction shown in Figures 3, 4 and 5, it is made with a threaded neck 10 by which it may be screwed onto the lower end of the pipe 11 forming the dust pocket in the gas flue 12.

The base has a valve port 13 surrounded by a flat sealing face 14 and a valve pad 15 forming a smooth continuation to one side of said sealing face.

Cooperating with the sealing face and with the lateral extension of the same is a valve disc 16 arranged to be slid over said faces by a lever 17 keyed at 18 to the actuating post 19 and having a sliding bearing at 20 with the inner face of a supporting or backing plate 21.

A special feature of the invention is that the backing plate is supported in parallel spaced relation to the base by means providing a clear and practically unobstructed way between and about said members so as to leave the moving elements of the valve operating in unconfined relation. The means for this purpose consists in the present disclosure of a series of studs or screw bolts 22 and nuts 23 fastening the supporting plate to the base against interposed spacing columns 24. In the case of the tank valve only three such fastenings are shown and for the dust valve (Figure 5), four such fastenings are illustrated, and said fastenings are arranged in both instances to leave a clear way in the line of travel of the valve so that solid objects deposited in the line of travel of the valve will be pushed out of the way by the valve disc without encountering any obstruction.

The coupling between the valve disc and actuating lever is shown as provided by a tubular projection 25 on the back of the valve disc entered in a socket 26 in the actuating lever and the sealing of the valve is effected by a spring 27 interposed between these coupling parts. This coupling permits independent rotative movement of the valve

disc. The lever is loosely keyed on the actuating shaft, as shown, so that it may adjust itself to slide freely over the back plate. A suitable lever or handle mechanism may be provided for turning the shaft or valve stem 19, such as indicated at 28.

If desired, the working parts of the valve may be protected against heavier solids or against mechanical injury by surrounding the same more or less with a guard or screen such as shown at 29 in Figure 1, said screen being indicated as a cupped screen or guard element inverted over the valve structure and secured to the back plate by the bolt 30.

In both constructions illustrated, the moving parts of the valve are unconfined about the sides and in the general plane of operation, leaving the valve element and lever free to push before them, such solids as might result from sedimentation or incrustation. The valve therefore is enabled to clear itself and to maintain itself in proper working condition irrespective of the solids carried by the fluid. In the dust valve construction shown in Figures 3 to 5, the valve parts operate in open air and so are more accessible than in the case of the tank valve first shown, but in both cases the main parts of the valve are accessible at the sides of the valve structure and so can be examined or relatively adjusted, as to free them from a binding condition, etc., without taking the valve apart.

The open space about the periphery of the valve body gives exceptional access of fluid to the valve element, making it unnecessary ordinarily to provide any port in the backing plate. This is the condition illustrated in Figure 1. If desired, however, the backing plate may be ported in line with the port in the base member, as shown at 31 in Figure 4. The strength of the spring 27 between the valve element and its actuating lever is sufficient to hold these parts in proper sliding engagement in the guideway between the parallel supporting surfaces in the valve body and its force always will be governed according as to whether the pressure of the fluid is acting to seat the valve as it is in Figure 1, or the valve disc is acting against the pressure of the fluid as it is in Figure 3.

What is claimed is:

1. In a valve of the character disclosed, a valve body having a port with a valve seat surrounding said port and a supporting surface forming a lateral continuation of said seat, a valve disc for sliding movement over said valve seat and lateral continuation, an operating member for shifting the valve disc, a backing for said operating member and means for supporting said backing spaced from the valve body and with openings about the sides of the valve between the base and backing to thereby enable the moving valve

disc to discharge solid matter lodged between the base and backing clear of the valve structure.

2. In a valve of the character disclosed, a valve body comprising a base with a port therein and a backing spaced in parallel relation to said base, said valve body being open about the sides of the same for lateral discharge of solid matter from between the base and backing, a valve element operable in the space between the base and backing, shiftable on the base over and away from the port therein and operative in such travel to discharge solid matter through the open sides between the base and backing, and a valve operating member having a portion thereof 80 slideable on said backing intermediate said valve element and said backing.

3. In a valve of the character described, a valve base having a port therein, a backing plate, bolts and spacers securing the backing plate in spaced parallel relation to the base and constituting the total means of connection between the base and backing plate to leave open spaces about the valve structure between said bolts and spacers, a valve disc slideable over the base, actuating means for said valve disc slideable over the backing plate, spring means forcing said valve element and actuating means apart and into sliding engagement with the respective supports therefor, said valve element and actuating means being exposed about the sides of the valve structure between the bolts and spacers and operative in their movements to 100 discharge solid matter through such spaces.

4. In a valve of the character disclosed, a valve body having members spaced to provide a guideway therebetween, said guideway being open at the side of the valve structure for the discharge of solid matter from said guideway, one of said members having a port therein, a valve element for closing said port, said valve element being slideable over the ported member and operative in its movement to discharge solid matter on the face of said member through the open side of the valve body and an actuating member for the valve element separate therefrom operative in the guideway aforesaid.

5. In a valve of the character disclosed, a valve body having members spaced to provide a guideway therebetween, said guideway being open at the side of the valve structure for the discharge of solid matter from said guideway, one of said members having a port therein, a valve element for closing said port, said valve element being slideable over the ported member and operative in its movement to discharge solid matter on the face of said member through the open side of the valve body and an actuating member for the valve element separate therefrom operative in the guideway aforesaid, said actuating member having a sliding movement over the

other member of the guideway and operative in its movement to discharge solid matter on the face of that member through the open side of the valve structure.

5 6. A valve comprising a ported base having a valve seat surrounding the port and a valve pad forming a lateral continuation of the valve seat, a valve disc slidable over said seat and extension valve pad, a backing plate 10 secured in spaced parallel relation to the base and with open space about the valve structure between the base and backing plate, an actuating member slidable over the inner face of the backing plate and having a driving 15 connection with the valve disc and spring means holding the valve element engaged with the valve seat and extension valve pad and the actuating means engaged with the backing plate, whereby in the movement of 20 said valve element and actuating means solid matter on the faces of the base and backing plate will be forced by the valve element and actuating means out through the open side of the valve structure.

25 7. In a valve, a valve body open about the peripheral portion of the same and having opposed parallel supporting surfaces, one of which is ported and surrounded by a valve seat, a valve element slidable over the ported 30 surface and operative in its movement to discharge solid matter on such surface through the open peripheral portion of the valve body and operating means for the valve element separate therefrom slidable over the opposed 35 supporting surface and operable in similar fashion to discharge solid matter through the open peripheral portion of the valve body.

In testimony whereof I affix my signature.

WYLIE G. WILSON.
